CLOTH FEEDING DEVICE FOR UNWINDING AND LAYING UP MACHINES

Herman Walter Gilbert, Kew Gardens, N. Y.

Application April 29, 1941, Serial No. 390,901

6 Claims. (Cl. 270—31)

This invention relates to new and useful improvements in cloth laying up machines, cloth unwinding machines, and similar equipment.

More particularly, the invention proposes cloth feeding devices for equipment as mentioned in the previous paragraph.

In the form of the invention which is applied to cloth laying up machines it is proposed to so construct the feeding device that it feeds the cloth at the same rate and in one direction as the lineal speed of the reciprocal carriage of the machine as it is moved in either direction.

In another form of the invention, it is proposed to characterize the cloth feeding device, when applied to unwinding machines, by an arrangement for feeding the cloth at predetermined speeds.

An important advantage of applying the cloth feeding device to cloth laying up machines, cloth unwinding machines and similar equipment resides in the fact that this equipment may be used to unwind or lay up cloth materials which should not be stretched, or subjected to material stretching stresses.

Still further it is proposed to characterize the cloth feeding device by a plurality of rollers rotatively mounted and arranged in an arcuate formation to support a roll of cloth, a prime mover and a transmission system from said prime mover to the rollers for turning said rollers simultaneously in one direction. When the cloth feeding devices are applied to cloth laying up machines it is proposed that the prime mover comprise a wheel of the cloth laying up machine which usually engages the table upon which the machine is reciprocally mounted. It is further proposed that in those instances in which the cloth feeding devices are applied to unwinding machines that the prime mover comprise an electric motor, preferably of variable speed.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a schematic side elevational view of a cloth laying up machine provided with a cloth feeding device constructed in accordance with this invention.

Fig. 2 is a fragmentary enlarged plan view looking in the direction of the line 2—2 of Fig. 1.

- Fig. 3 is a fragmentary vertical sectional view taken on the line 3—3 of Fig. 2.

Fig. 4 is a fragmentary elevational view looking in the direction of the line 4—4 of Fig. 2.

5 Fig. 5 is a fragmentary enlarged vertical sectional view taken on the line 5—5 of Fig. 4.

Fig. 6 is a horizontal sectional view taken on the line 6—6 of Fig. 5.

10 Fig. 7 is a fragmentary enlarged elevational view looking in the direction of the line 7—7 of Fig. 6.

15 Fig. 8 is a fragmentary vertical sectional view taken on the line 8—8 of Fig. 7.

Fig. 9 is a transverse vertical sectional view of an unwinding machine provided with a cloth feeding device constructed in accordance with this invention, this section being as though taken on the line 9—9 of Fig. 10.

20 Fig. 10 is a fragmentary elevational view of the unwinding machine shown in Fig. 9, looking in the direction of the line 10—10 of Fig. 9.

Fig. 11 is a fragmentary vertical sectional view taken on the line 11—11 of Fig. 10.

25 In the form of the invention illustrated in Figs. 1—8 inclusive, a cloth feeding device constructed in accordance with this invention is shown applied to a laying up machine 15. As the details of the cloth laying up machine form no part of this invention they will be omitted from

30 this specification, particularly in view of the fact that such machines are generally known in the trade. However, it is necessary that the cloth laying up machine 15 be provided with a reciprocal carriage 16 having a wheel 17 engaging a

35 table element 18 so as to turn in one direction or the other, depending upon which direction said carriage is being moved. The table element 18 may comprise a track on the table, or the table surface, depending merely upon the design of the

40 machine. The particular machine schematically shown in Fig. 1 includes the usual cloth gripper devices 19 mounted upon the table 18, at the ends of the strokes of reciprocation of the carriage 16. Since these gripper devices are generally known in the trade, and form no part of the present invention, the details thereof will be omitted.

45 The cloth feeding device, in accordance with this invention, includes a plurality of support elements or rollers 20 rotatively mounted on the carriage 16 and arranged so as to have their axes parallel with each other and in arcuate formation, as clearly shown in Figs. 1 and 4, so as to be capable of supporting a roll of cloth material

50 21 which is to be laid by the laying up machine.

While the drawings illustrate but three rollers 20, it should be clearly understood that more or less may be used. The web 22 from the roll of cloth 21 is illustrated extended upwards over the cloth guiding means, not shown in detail, of the cloth laying up machine 15. A plurality of endless members or bands 23 are mounted transversely across and in grooves 20b of the rolls 20 to assist in holding the roll of cloth 21. These bands 23 may be provided in suitable numerical quantities at suitable spaced positions from each other so as to support the roll of cloth 21 without having portions bellying downwards between the rollers 20. Means is provided for driving the rollers 20 in one direction at speeds calculated to feed the web 22 from the roll 21 at the same speed as the lineal speed of travel of the carriage 15 of the laying up machine during use.

The means referred to at the end of the previous paragraph, includes a rotative shaft 24 mounted upon the carriage 16. A transmission from the wheel 17 connects with the shaft 24 and includes means for causing said shaft 24 to rotate in one direction at speeds in proportion to the speed of said wheel 17 while turning in one or the other direction as the carriage 16 is reciprocated during use. This transmission includes a gear 25 coaxially fixedly mounted on the wheel 17 and of a slightly smaller diameter than the gear wheel 17 so that the outer diameter of the gear 25 does not contact the table 18.

The means for causing the shaft 24 to rotate in one direction, as stated, comprises a double clutch consisting of a relatively wide inner clutch member 26 having several peripheral cutouts 27 over which gear wheel 28 and 29 rotatively engage. Each cutout 27 is provided with a ball 30. Each cutout 27 has a low end and a high end arranged relatively in the same direction, and so constructed that when the balls 30 are in the deep portions of the cutouts the gear wheels are free to turn; and when in the shallow portions, they will catch. The inner member 26 is secured to the shaft 24 by a key 31. The gear 28 directly meshes with the gear 25. The gear 29 meshes with an idler gear 32 rotatively supported on a stud 33 mounted on the carriage 16. This idler 32 meshes with the gear 25. The arrangement is such that when the wheel 17 turns in one direction the gears 28 and 29 will turn in opposite directions. However, only one of these gears will have its rotations transmitted to the shaft 24 because of the construction of said transmitting double clutch.

A transmission is also provided from the shaft 24 to turn the rollers 20 in one direction at speeds in proportion to the speed of the wheel 17 turning in either direction. This transmission system includes a pulley 35 mounted on the shaft 24 and engaged by a belt 36 which is supported by a pair of spaced rotatively mounted idler pulleys 37 mounted on the carriage 16. These idler pulleys are so positioned that a section 36a of the belt 36 engages tightly against the bottom sides of pulleys 38 mounted upon the ends 20a of the rollers 20. The construction is such that the belt 36 transmits the rotations from the shaft 24 indirectly to the rollers 20.

The operation of the device is as follows:

The cloth laying up machine 15 is used in the conventional way. However, simultaneously with its operation, the cloth feeding device functions so as to feed out the web 22 from the cloth roll 21 at the same speed as the lineal speed of

the carriage 16 of the cloth laying up machine. This will eliminate any stretching tendencies of the web 22 while it is being laid up by the cloth laying up machine.

When the carriage 16 is reciprocated, the wheel 17 will be correspondingly turned. This wheel will turn in direct proportion to the speed and distance that the carriage 16 is being moved. The rotations from the wheel 17 are transmitted to the double clutch shown particularly in Figs. 5, 6 and 8 so as to drive the shaft 24 in one direction, at a speed in proportion to the rotations of the wheel 17 in either direction. The rotations from the shaft 24 are transmitted indirectly to the rollers 20. Since the rollers 20 support the roll of cloth 21, the cloth roll 21 will turn and thus the cloth web 22 will be fed out. The transmission systems are so designed that the cloth web 22 will be fed at the same lineal speed as the lineal speed of reciprocation of the carriage 16.

In Figs. 9 to 11 inclusive a modified form of the invention has been disclosed. In this form of the invention the cloth feeding device is applied to a cloth unwinding machine, generally indicated by reference numeral 40. The details of this unwinding machine will not be given in this specification as it forms no part of the invention and similar devices are generally known in the trade. However, the cloth unwinding machine 40 is characterized by a frame 41 across which a plurality of support elements or rollers 42 are rotatively mounted. These support elements or rollers 42 are arranged in an arcuate formation so as to support a roll of cloth, schematically indicated by reference numeral 43, which is being unwound on the unwinding machine. The web 44 from the roll of cloth 43 is shown extended upwards and engaged over a roller 45 of the unwinding machine.

The cloth feeding device, in accordance with this invention, includes a prime mover 46, such as an electric motor preferably of variable speed. A transmission system is provided from the prime mover 46 to rotate the rollers 42 simultaneously, and in one direction. This transmission system includes a pulley 47 on the shaft of the motor 46 and engaged by an endless belt 48 which engages over several idler pulleys 49 rotatively mounted on the frame 41 of the cloth unwinding machine. The endless belt 48 has a section 48a which extends beneath and engages a plurality of pulleys 50 which are mounted on the end portions 42a of the rollers 42. The arrangement is such that rotations from the motor 46 is transmitted to simultaneously rotate the pulleys 50 in one direction, and these rotations are transmitted to the rollers 42.

The rollers 42 are provided with a plurality of endless members or bands 51 engaged transversely thereof. These bands 51 are merely for the purpose of facilitating the support of the roll of cloth 43 without allowing portion of the roll to sag in the areas between the rollers 42. At the points where the bands 51 engage the rollers 42, the rollers 42 are formed with grooves 52. These grooves are of a depth corresponding to the thickness of the material from which the bands 51 are constructed. The grooves 52 prevent the bands 51 from shifting along the lengths of the rollers 42. However, in practice the grooves 52 may be omitted, if desired.

The operation of the device is as follows:

A roll of cloth 43 is placed on the unwinding machine, and the web 44 is extended upwards.

Heretofore it was customary to pull the web 44 to unwind the roll 43. However, with certain types of cloth this pulling operation is objectionable. In accordance with this invention it is merely necessary to set the electric motor 46 into operation. This will cause the rollers 42 to turn and feed out the web 44 at a predetermined speed. This speed may be equal to the speed at which it is desired to unwind the roll 43 or may be slightly less than this speed so that a small amount of pull on the web 44 is necessary. However this operation is merely a matter of taste. The important feature resides in the fact that the web 44 is being fed without the requirement of a pull upon it.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a cloth handling machine of the class described having a plurality of rollers rotatively mounted and arranged in an arcuate formation to support a roll of cloth, a prime mover, a transmission system from said prime mover to said rollers for turning said rollers simultaneously in one direction, and an endless member engaged over said rollers for assisting in supporting said roll of cloth.

2. In a cloth handling machine of the class described having a plurality of support elements rotatively mounted and arranged in an arcuate formation, a prime mover, a transmission system from said prime mover to said support elements for turning said support elements simultaneously in one direction, and an endless member engaged over said support elements for supporting a roll of cloth.

3. In a cloth handling machine of the class described having a plurality of rollers rotatively mounted and arranged in an arcuate formation to support a roll of cloth, a prime mover, a transmission system from said prime mover to said rollers for turning said rollers simultaneously in one direction, and bands engaged over said rollers for assisting in supporting said roll of cloth.

4. In a cloth handling machine of the class described having a reciprocal carriage provided with a wheel engaging a table element so as to turn in one direction or the other depending upon which direction said carriage is being moved, a plurality of rollers rotatively mounted on said carriage and arranged in an arcuate for-

mation to support a roll of cloth, a rotative shaft on said carriage, a transmission from said wheel to said shaft and including means for causing said shaft to rotate in one direction at speeds in proportion to the speed of said wheel while turning in one or the other directions, a transmission system from said shaft to said rollers for turning said rollers in one direction at speeds in proportion to the lineal speed of motion of said carriage, and a plurality of bands engaged over said rollers for assisting in supporting said roll of cloth.

5. In a cloth handling machine of the class described having a reciprocal carriage provided with a wheel engaging a table element so as to turn in one direction or the other depending upon which direction said carriage is being moved, a plurality of rollers rotatively mounted on said carriage and arranged in an arcuate formation to support a roll of cloth, a rotative shaft on said carriage, a transmission from said wheel to said shaft and including means for causing said shaft to rotate in one direction at speeds in proportion to the speed of said wheel while turning in one or the other directions, a transmission system from said shaft to said rollers for turning said rollers in one direction at speeds in proportion to the lineal speed of motion of said carriage, comprising a pulley coaxially mounted on each roller, an endless belt having a portion engaging against the sides of said pulleys, and a pulley on said rotative shaft engaging said endless belt.

6. In a cloth handling machine of the class described having a reciprocal carriage provided with a wheel engaging a table element so as to turn in one direction or the other depending upon which direction said carriage is being moved, a plurality of rollers rotatively mounted on said carriage and arranged in an arcuate formation to support a roll of cloth, a rotative shaft on said carriage, a transmission from said wheel to said shaft and including means for causing said shaft to rotate in one direction at speeds in proportion to the speed of said wheel while turning in one or the other directions, a transmission system from said shaft to said rollers for turning said rollers in one direction at speeds in proportion to the lineal speed of motion of said carriage, comprising a pulley coaxially mounted on each roller, an endless belt having a portion engaging against the sides of said pulleys, and a pulley on said rotative shaft engaging said endless belt for driving it, and idler pulleys assisting in supporting said endless belt so as to support said section engaging said pulleys.

HERMAN WALTER GILBERT.
